CLAIM

The ornamental design for an adaptor assembly for a stroller, as shown and described.

DESCRIPTION

FIG. 1 is a perspective view of an adaptor assembly for a stroller showing our new design.

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1; and,

FIG. 8 is a view showing the stroller frame shown in FIG. 1 in use.

The broken line showing is included for the purpose of illustrating environmental structures and forms no part of the claimed design.
